UNITED STATES PATENT OFFICE

THEODORE A. FEDERWITZ, OF PHILADELPHIA, PENNSYLVANIA, ASSIGNOR TO STOKES & SMITH COMPANY, OF PHILADELPHIA, PENNSYLVANIA, A CORPORATION OF PENNSYLVANIA

AUTOMATIC GLUING MACHINE

Application filed April 29, 1927. Serial No. 187,646.

My invention relates to a mechanism for applying a coating, as of adhesive, in succession to a series of wrappers, labels, sheets or the like, hereinafter termed "sheets".

5 In accordance with my invention a coating of adhesive applied to a distributing roller adapted to engage a sheet to be coated, is smoothed by a member, preferably intermittently rotatable, and more particularly, also 10 cylindrical in cross section, positioned in close, spaced relation to the distributing roller, and preferably interposed between the distributing roller and a supply roller.

Further in accordance with my invention, 15 the intermittently rotatable member is actuated in timed relation with respect to the delivery of an object or a series of objects in succession to the distributory roller by the feeding mechanism for said objects.

20 My invention resides in mechanism of a character hereinafter described and claimed.

Fig. 1 is a fragmentary elevational view partly in section of an automatic gluing machine in which my invention is incorporated.

25 Fig. 2 is a detail view of parts disclosed in Fig. 1.

Fig. 3 is a fragmentary end view in elevation, with parts in section, of Fig. 1.

Fig. 4 is a detail arrangement of the sup- 30 plying, transfer and applying rolls.

Referring to the drawings, there are supported upon the base or frame 1 channel shaped track members 2, in which roll in a rectilinear path the rolls 3 mounted upon stub 35 shafts 4, mounted upon and supporting the carriage 5. Secured upon the rock shaft 6 are the levers 7 to whose upper ends there are pivoted at 8 the link structures 9, pivoted to the carriage 5 at 10, whereby the carriage 5 40 and the parts supported thereon are reciprocated forwardly and backwardly for each sheet fed.

Upon the vertically movable table or support 11, is disposed the stack S of sheets to 45 be removed therefrom in succession.

By mechanism, not shown, but fully de- 50 scribed in application Serial No. 3,316, filed January 19, 1925, the table 11 is moved upwardly as the stack S diminishes in thickness.

Disposed upon the carriage 5 are upwardly

and rearwardly extending arms 18 in which is pivoted the shaft 19 upon which is secured the forwardly extending arms 20 in which is pivoted the suction roll 21 having a suction port 27 communicating with the core 28 continuously connected through pipes and tubes not shown, with a vacuum pump.

Adjustably secured to the carriage member 5 are the brackets 5^a, to which is secured a bar 31 extended transversely to opposite sides of machine and supported upon bar 31, are the bearings 32 of the idler feed rolls 33. Supported upon the bar is the tongue or guide member 35 whose rear edge 36 is presented to the sheets as they are lifted by the suction roll 21, and whose surface 37 guides the sheet to the feed roll 33.

Supported upon the frame 1 and positively driven, is the feed roll 38 between which and the feed roll 33, each sheet is clamped as it is withdrawn from the stack and fed by the rolls 33 and 38 to the feed rolls 39 and 40, driven and idling, respectively, which advance the sheet from the guide member 41 to the glue or adhesive distributing roll 42 and the co-acting guide roller 43. These rolls advance the sheet onto the conveyor belt 44 which passes over the roller 45, as well understood in the art.

The connection between the vacuum pump and the suction roll 21 includes a relief valve for discontinuing suction, which is periodically operated by a member movable with the carriage 5 as is described in the application above referred to.

The parts so far described are indicated in Fig. 1 in their positions at the beginning of a cycle, the carriage 5 and parts carried thereby being in their extreme forward position. Shortly before reaching that position, suction is applied to the roller 21 so that as the carriage 5 and therefore the roller 21 approach the forward limit of travel, the latter is brought sufficiently close to the stack S to draw up the uppermost sheet. Thereafter the carriage moves rearwardly, as the driving cam 13 continues to rotate, drawing the sheet along, accompanied by an upward and rearward movement of the roller 21 as by movement of inclined channel tracks, not

shown, and simultaneously the roller 21 is rotated in a clockwise direction.

After predetermined extent of rearward movement of the carriage 5 and roller 21, the vacuum is broken, releasing the sheet 6 from roller 21, whereupon the forward end of the sheet falls upon the guide surface 37 of the member 35. Continued rearward movement of the carriage 5 moves the tongue 35 with relation to the sheet, which elevates the forward end of the sheet to such position that when the roller 33 comes into contact with driven feed roll 38, it is clamped between them and advanced upwardly to the left by clockwise rotation of roller 38 towards feed rolls 39 and 40 over the guide 41. The cycle is completed when the parts are approximately in the position shown in Fig. 2. The sheet is forced into engagement with the feed rollers 39 and 40, thence between the adhesive coated roll 42 and the idler roller 43; and thence to the conveyor belt 44.

The roller 42 is supplied with adhesive from a receptacle or tank 46 suitably supported by the frame 1. The periphery of the roller 47 which is continuously driven in a clockwise direction by gears 48 and 49 mounted respectively on the shafts of rollers 42 and 47, dips below the surface of the adhesive and transports it to the upper side of the roller, the scraper 50 being adjusted to permit only the passage of a quantity sufficient to maintain a suitable fountain of glue between the rollers. The speed of rotation of the roller 47, which has the additional function of keeping the adhesive mixed by rotating in it, is slow, to prevent excessive agitation which would result in foaming of the glue.

Previously, in mechanism of this character 40 the fountain was maintained between two, continuously rotating rollers in close, spaced relation. With such construction, the coating of adhesive on the roller corresponding to roller 42 was not uniform or smooth but non-uniform and ridged, due to the surface tension of the glue. In addition, the rotation of both the supply roller and distributing roller in close relation to each other caused 50 the glue to foam due to the "candy pulling effect" injecting a considerable amount of air into the glue.

My invention contemplates agitating the glue and transporting it to the vicinity of the distributing roller, that is, to a pocket formed by the distributing roller and a scraper member. The transported adhesive, instead of forming a fountain between closely-spaced rotating rollers as heretofore, is transferred 60 to a scraper member 51 resting against or in close, spaced relation to the distributing roller 47 so that a wiping action instead of a pulling out action of the glue results. As a consequence the glue does not foam or form 65 ridges on the distributing roller. In the

specific embodiment of my invention disclosed, the roller 47 both agitates the glue and transports it. It is to be understood, however, that the adhesive may be agitated and transported by separate means or by a single means other than a roller. 70

Referring to Fig. 1, there is interposed between the adhesive supplying and the adhesive applying rollers, a third roller 51 mounted on a shaft 52 whose ends are supported by the brackets 53 pivotally mounted on the cross-rod 54 extending between the side frames 1. Each of the brackets 53 is provided with an offset extension 55 having threaded engagement with the adjusting screw 56 equipped with a hand wheel for convenience of manipulation, to control the thickness of the coating on the roller 42. 75

On a prolongation of shaft 52 is mounted as shown most clearly in Fig. 3, a ratchet disk 57 whose rear face contains a circular series of indentations 58 which successively co-operate with the spring-pressed locking pawl 59 normally to retain the roller 51 in a stationary position with respect to roller 42. 85 The roller 51 when stationary serves as a straight-edge and smoothes the glue adhering to the roller 42, so that the coating of adhesive as applied to a sheet S is of substantially uniform thickness throughout, insuring a well wrapped box or article of neat appearance. 95

The teeth in the periphery of the ratchet disk engage an actuating pawl 59^a pivoted at one end of a lever 60 and maintained in engagement with the ratchet disk by suitable biasing means as a spring 61. The lever 60 is pivoted intermediate its ends on a stud shaft 62 threaded into the upper end of a standard 63 bolted or otherwise suitably fastened at its base to the frame 1. A spring 64 positioned between the lower end of the lever 60 and an extension 65 of the standard 63 normally maintains the lever in engagement with an adjustable abutment 66, which may be as shown, a screw threaded through an offset extension of the standard and provided with a locking nut. 105

Passing freely through extension 65 and an end of lever 60, is a rod or shaft 67 fastened to and movable with carriage 5, whose free end is threaded and receives movable abutments 68 of such size or shape, or both, that they can not pass through the hole in lever 60. 115

As the sheet-feeding mechanism before described nears the completion of its cycle of operation, the abutments 68 at a time determined by their position on the shaft 67, are moved by the carriage 5 into engagement 125 with the lever 60, causing it to rotate about the shaft 62. The pawl 59^a moves the roller 51 through an angle whose magnitude depends upon the original position of lever 60 which is determined as before stated by the 130

stop pin 66. As the face of the locking pawl or detent 59 is cone shaped, it offers but little resistance to the actuation by the pawl 59^a. When the carriage 5 reverses its movement, the spring 64 returns the lever 60 to its original position, the pawl 59^a riding idly over the ratchet teeth.

While the roller 51 is stationary, it functions as a scraper and normally, if it were permitted to remain in such condition, would collect a considerable amount of foreign matter which after a time would contaminate the glue, collect in lumps or projections and defeat the very purpose of the stationary roll. Further the roller surface under that condition would be subjected to wear which would destroy its utility.

By intermittently rotating the roller 51 at comparatively short intervals, there is prevented any accumulation of foreign matter in the adhesive reservoir between the rolls. In other words, a cleaning operation is effected. It should also be noted that the direction of rotation is such that a fresh supply of adhesive is transported by the roller 51 to the well of a reservoir between rollers 51 and 42 each time that it is stepped around by the pawl. It is apparent also that by such rotation, any wear is distributed over the entire surface of the roller.

As the rotation of this roller is timed, as explained above, with respect to the sheet to which glue is to be applied, ordinarily the portion of the roller 42 at which there is any slight irregularity of the adhesive layer due to relative movement of rollers 42 and 51 for a brief interval, does not come into contact with the sheet to which glue is to be applied.

It is to be understood that in the broad aspect of my invention, it is not essential that the member 51 rotate at all to prevent the undesirable foaming and ridges referred to and further, that if such member is rotated for the purposes stated, it is not necessarily circular in cross-section. Preferably, however, it is cylindrical and rotates periodically in timed relation to the sheet-feeding mechanism.

What I claim is:

1. In a machine for applying a coating of adhesive to individual sheets, a distributing roller adapted to engage said sheets in succession, a roller to transport adhesive, a rotatable member interposed between said rollers in close, spaced relation to said distributing roller, and means intermittently to rotate said rotatable member.

2. In a machine for applying a coating of adhesive to individual sheets, a distributing roller adapted to engage said sheets in succession, a roller to transport adhesive, a rotatable member interposed between said rollers in close, spaced relation to said distributing roller, and means intermittently to ro-

tate said rotatable member in a direction opposite to that of said distributing roller.

3. In a machine for applying a coating of adhesive to individual sheets, a distributing roller adapted to engage said sheets in succession, a roller to transport adhesive, a third roller interposed between said rollers in close, spaced relation to said distributing roller, and means intermittently to rotate said third roller.

4. In a machine for applying a coating of adhesive to a sheet, a distributing roller adapted to engage said sheet, a roller to agitate and transport adhesive, and a member interposed between said rollers in close, spaced relation to said distributing roller and stationary with respect thereto to effect smoothing of an adhesive coating on the surface of said distributing roller.

5. In a machine for applying a coating of adhesive to individual sheets, a distributing roller adapted to engage said sheets in succession, a roller to agitate and transport adhesive, a rotatable member interposed between said rollers in close, spaced relation to said distributing roller, and means intermittently to rotate said rotatable member.

6. In a machine for applying a coating of adhesive to a sheet, a distributing roller adapted to engage said sheet, a roller to agitate and transport adhesive, a normally stationary third roller interposed between said rollers in close, spaced relation to said distributing roller, and means intermittently to rotate said third roller.

7. In combination, a roller, means to supply adhesive to said roller, means to feed in succession a series of sheets to said roller, a rotatable scraper member in close, spaced relation to said roller, and means operating in timed relation to said feeding means intermittently to rotate said rotatable means.

8. In combination, a roller, means for applying a coating of adhesive to said roller, means to feed in succession a series of sheets to said roller, rotatable means in close, spaced relation to said roller normally stationary to smoothen said coating, and means intermittently operating in timed relation to said feeding means to rotate said rotatable means in a direction opposite to that of said roller.

9. In a machine for applying a coating of adhesive to a series of sheets in succession, an adhesive applying roller adapted to engage said sheets successively, an adhesive-trans- porting roller, a rotatable scraper means interposed between said rollers, and means operating in timed relation to delivery of sheets to said first roller intermittently to rotate said rotatable means.

10. In a machine for applying a coating of adhesive to a series of sheets in succession, an adhesive-applying roller adapted to engage said sheets successively, an adhesive-supplying roller, rotatable scraper means interposed

between said rollers, and means operating in timed relation to delivery of sheets to said first roller intermittently to rotate said rotatable means in a direction opposite to that of said first named roller.

5 11. In a machine for applying adhesive to a series of sheets in succession, an adhesive-applying roller adapted to engage said sheets successively, an adhesive supply roller therefor, a third roller interposed between said first named rollers, and means operating in timed relation to delivery of sheets to said first roller intermittently to rotate said third roller.

10 12. In a machine for applying a coating of adhesive to a sheet, a distributing roller adapted to engage said sheet, an essentially non-rotating scraper member positioned adjacent said roller and forming a pocket, a container for adhesive, and a slowly revolving roller to agitate adhesive in said container and to transport it to said pocket to form a fountain of adhesive.

15 13. In a machine for applying a coating of adhesive to individual sheets, an adhesive-coated roller adapted to engage said sheets, means to apply adhesive to said roller, a member having increments of surface adapted individually to be positioned closely adjacent said roller to smoothen adhesive thereon, and means intermittently to actuate said member to present a fresh surface thereof.

20 14. In a machine for applying a coating of adhesive to individual sheets, a roller adapted to apply adhesive to said sheets, means to apply a coating of adhesive to said roller, rotatable means closely adjacent the coated surface of said roller, and means intermittently to rotate said means in direction opposite to direction of rotation of said roller.

25 15. In a machine for applying a coating of adhesive to a sheet, an adhesive-coated roller adapted to engage said sheet, a scraper member adjacent said roller and stationary with respect thereto to smoothen the adhesive-coating thereon, and means to transport adhesive to the region of proximity of said roller and scraper.

30 16. In a machine for applying a coating of adhesive to a sheet, a continuously revolving distributing roller adapted to engage said sheet, a continuously revolving adhesive transporting roller, and an essentially non-rotating wiping member disposed between said rollers and in close spaced relation to said distributing roller to smoothen adhesive thereon.

THEODORE A. FEDERWITZ.
